US00D836672S

(12) **United States Design Patent** (10) **Patent No.:** **US D836,672 S**
(45) **Date of Patent:** **** Dec. 25, 2018**

(54) **DISPLAY SCREEN OR PORTION THEREOF WITH GRAPHICAL USER INTERFACE**

(71) Applicant: **Apple Inc.**, Cupertino, CA (US)

(72) Inventors: **Gary William Gehiere**, Santa Clara, CA (US); **Alexander Charles Maclean**, San Jose, CA (US)

(73) Assignee: **Apple Inc.**, Cupertino, CA (US)

(**) Term: **15 Years**

(21) Appl. No.: **29/642,806**

(22) Filed: **Apr. 2, 2018**

Related U.S. Application Data

(63) Continuation of application No. 29/597,634, filed on Mar. 17, 2017, now Pat. No. Des. 814,487, which is a continuation of application No. 29/569,645, filed on Jun. 29, 2016, now Pat. No. Des. 781,909, which is a continuation of application No. 29/529,916, filed on (Continued)

CLAIM

The ornamental design for a display screen or portion thereof with graphical user interface, as shown and described.

DESCRIPTION

FIG. 1 is a front view of a display screen or portion thereof with graphical user interface showing the claimed design; and,

FIG. 2 is another embodiment thereof.

The broken lines in the figures show a display screen or portion thereof, and form no part of the claimed design.

1 Claim, 1 Drawing Sheet
